UNITED STATES PATENT OFFICE.

JOHN ALWYN KELLER, OF BAY SHORE, NEW YORK, ASSIGNOR TO KELLER PRINTING COMPANY, OF NEW YORK, N. Y., A CORPORATION OF NEW YORK.

MACHINE FOR PRINTING TICKETS.

Application filed April 11, 1923. Serial No. 631,345.

To all whom it may concern:

Be it known that I, JOHN ALWYN KELLER, a citizen of the United States, and resident of Bay Shore, in the county of Suffolk and 5 State of New York, have invented certain new and useful Improvements in Machines for Printing Tickets, of which the following is a specification.

This invention relates to machines for 10 printing tickets, and it has particular relation to an improved mechanism for imprinting the "lot numbers" or other identifying data successively upon clothing tickets which are to be attached to garments or 15 upon other or analogous tickets which are fed through the machine in continuous strips comprising successively the respective ticket units.

My present improvements are directed 20 especially to the class of such ticket-printing machines which is known as "non-automatic," in that the printing media is set in desired status and does not itself vary or change automatically to imprint successive 25 or different numbers or figures, but is manually readjusted or set to vary the imprint.

The object of my invention is to provide 30 a simple and improved mechanism of the character set forth, which will possess advantages in point of convenience in adjustment or "setting" of the printing media, positive and effective action, economy in 35 construction and general efficiency.

In the drawings—

35 Figure 1 is a perspective view of a ticket-printing machine embodying my invention.

Fig. 2 is a vertical longitudinal sectional view through the machine on the plane of the main shaft which carries the printing 40 media.

Fig. 3 is a vertical cross-section on the line 3—3, Fig. 2.

Fig. 4 is a detail face view of the head of the main shaft and the printing media 45 carried thereon.

Fig. 5 is a detail cross-section on the line 5—5, Fig. 4.

Fig. 6 is a detail cross-section on the line 6—6, Fig. 4.

50 Fig. 7 is a detail perspective view of one of the type discs.

Fig. 8 is a detail face view of the platen drum.

Corresponding parts in all the figures are denoted by the same reference characters. 55

Referring to the drawings, I have herein illustrated one of the usual types of ticket-printing machines to which my invention and improvements are adapted, and 14 designates a framework which comprises a 60 bearing, 15, for the main revoluble shaft, 16, upon which the printing media is mounted, and another bearing, 17, for the revoluble shaft, 18, which carries the platen drum, 65 said shafts being mounted horizontally with the shaft 18 beneath the shaft 16 and respectively carrying intermeshing gears, 19—20, whereby their revolution in reverse directions is effected under action of a crank-handle, 21, carried by the main shaft 16, or 70 other suitable driving means. Said framework also comprises a top arm, 22, carrying a fixed shaft, 23, upon which is mounted an inking roller, 24, preferably as an "idler," 75 in a plane in which the surface of the inking roller will intermittently contact with the type-heads of the printing media carried by the revoluble main shaft 16 and be advanced in a revoluble step-movement by such contact. Said inking roller is preferably ad- 80 justably mounted with relation to its contact with the printing media, such adjustment being by means of a slot, as indicated at 25, in the frame arm 22, in which the end of the fixed shaft 23 is seated and secured 85 by a set-nut, 26. The framework 1 also carries a feed table, 27, leading to the impression surface of the platen drum, along which the continuous ticket-strip, shown at 28, is fed and guided for the imprint upon 90 its respective ticket units.

The foregoing general features of construction and associate arrangement of parts is as usual in the type of ticket-printing machines in connection with which the embodiment of my present invention and improvements is herein illustrated. Usually, in such machines, the main shaft 16 has been provided with a cylindrical head having one or more longitudinal grooves or recesses in 100 its peripheral or circumferential surface, in which groove or socket individual type are seated and set in desired series and alignment, as in a printer's composing-stick, and secured in set position by compression screws 105 operative in the end of said shaft-head and

bearing against the end of the series of set type to clamp the latter in their seat in the groove and with their printing face in projective position therefrom. Such construction is inconvenient and insecure, and requires much handling and manipulation and removal and insertion of the individual type units in the setting and securing process and in effecting any change in the type-setting 10 to vary the imprint.

In my invention the printing media in all its variable setting and adjustments is permanently carried by the head of the revolute main shaft, 16, and can be varied in its 15 "set" to produce any desired change in the imprint, and securely locked in its re-set, without removal from the shaft-head. The printing media thus operative and mounted is constituted by a series of type-discs, 29, 20 which are mounted to permit a revolute step-movement and respectively have a series of variable printing characters extending circumferentially of their periphery and forming type-heads, as at 30. Said series of 25 type-discs are mounted side by side and in alignment and collectively constitute a printing-drum.

I have herein shown my improvements as adapted for printing a "lot number" upon 30 the successive units of the continuous ticket-strip, and for this purpose each type-disc 29 has at its periphery a continuous series of equi-distantly spaced numerals constituting ten units from "1" to "0" inclusive and 35 forming type-heads, as at 30. Thus, when the type-discs are mounted side by side with their respective type-heads 30 in alignment, the type-heads collectively form a desired set of numbers extending across the 40 printing-drum constituted by the type-discs, and by turning the respective type-discs in a revolute step-movement with relation to their common axis the transverse set of numbers for the imprint will be 45 altered or changed as desired. When the printing characters of the type-discs are constituted by numerals, for imprinting "lot numbers" or analogous uses, a portion of the periphery between the numerals "1" and 50 "0" is left blank, as at 31, and the set of numerals may also be supplemented by a type-head "dash" or hyphen following the "0", as at 32, and thus the set of type-discs 55 may be adjusted to imprint any desired "number" or set of numbers from "1" to (for instance) "1 000 000", according to the plurality of type-disc units employed for the printing-drum.

It will therefore be understood that any 60 desired variation or adjustment of the imprint, according to the character of the type-heads 30 as employed upon the set of type-discs, may be accomplished in the adaptation of my improvements to divers 65 purposes in printing ticket-strips, and that

any desired number of type-discs and any desired variation in the co-related printing characters forming the type-heads of the respective type-discs may be employed.

The type-discs constituting the printing-drum are collectively mounted upon a fixed shaft, 33, and in "re-setting" are operative as "idle" on said shaft, the mounting of the shaft being in a plane beyond the axis of the revolute main drive-shaft 16 and its head, 34, whereby the axis of the type-discs in their revolute step-movement in re-setting is eccentric to the axis of the main shaft 16 and the printing-drum constituted by the type-discs is thus eccentric to the axis of said main shaft and carries the type-heads 30 in projective position beyond the arc of a circle having its center at the axis of said main shaft 16.

In the preferred construction for effecting the conditions above set forth, the head, 34, carried by the main shaft 16 is recessed or cut away to form an open body portion affording a platform or seat, as at 35, extending beyond the inner wall or flange, 36, of the head, the depth of said open body portion being preferably on a plane beyond the axis of the shaft 16 and head 34. The periphery or surface of the head, as at 37, beneath the platform 35, and the periphery of the end flange 36, are cylindrical in contour, conforming to a circle having its center at the axis of the shaft 16, and the shaft carries the head in a revolute movement by fixed connection with said end wall or flange 36.

A boxing or framework, 38, for carrying the printing-drum, is seated and fixed within the open body portion of the shaft-head 34 and upon the platform 35 and comprises 105 end walls, 39-39, connected by transverse base-plates, 40, the latter being seated upon the head-platform 35 with the inner end wall 39 against the outer face of the end wall or flange 36 of the shaft 16. The shaft-head 34 with its end flange 36 and the boxing or framework 38 are respectively 110 preferably formed integrally from a metallic block or body, and said printing-drum boxing 38 is preferably detachably secured 115 to the shaft-head by means of screws, as at 41, having countersunk heads at the under surface 37 of said head and entering the cross base-plates 40 of the boxing. The fixed shaft 33 which constitutes the mounting for the type-discs extends between the end walls 39 of the boxing 38 and is carried thereby, preferably in detachable connection by means of screw-fastenings, as at 120 42-43, the plane of said shaft being a suitable distance above the base of said boxing.

The means for locking the type-discs 29 in their manually-set adjustment or position is preferably constituted by a pawl and ratchet construction. In such locking means 130

as herein shown, each type-disc is provided at one face with a laterally-projecting side plate, 44, preferably integral with the disc and surrounding the central idler-bearing opening, 45, thereof, said lateral portion having a cylindrical periphery provided with equidistant ratchets, 46, located with relation to each type-head 30 in the revoluble step-movements of the disc. A series 10 of pawls, 47, are mounted with relation to the respective type-discs, with their locking points, 48, entering between the respective discs of the series constituting the printing-drum and respectively engaging the ratchets 46 thereof, said pawls preferably consisting of metallic plates of suitable contour. The series of pawls are pivotally mounted at their lower ends upon a cross-pin, 49, extending between the end walls 20 39 of the boxing 38 at a point above the base and near the front thereof, and each pawl is controlled in its normally-fixed engagement with the disc-ratchets 46 by a spring arm, 50, projectively carried by a plate, 51, 25 fastened at its lower portion to the front edge of the cross base-plate 40 of the boxing 38 at the front of the latter, said spring arms respectively bearing against the outer edge of the respective plate-pawls 47.

30 Under the foregoing construction, the adjustment or re-setting of the respective type-discs 29 can be conveniently effected by springing the respective spring control-arms 50 outwardly, by means of a suitable tool 35 or implement, to release the bearing upon the pawl-plate 47, and then turning the type-disc manually in its desired "idler" step-movement to "set" the desired type-head 30, after which the spring arm is released and 40 is again operative to retain the pawl in locking engagement with the disc-ratchet 46. Thus, the alignment of the type-heads of the set of type-discs can be varied to produce the desired imprint and the discs 45 locked in adjusted position, by convenient manipulation without removing any part of the printing media from the carrying-head of the main drive-shaft 16, and it will be further noted that the improved construction 50 as above described enables the removal of the printing-drum and its carrying boxing or framework 38 from the shaft-head 34 and the removal of the shaft and discs of the printing-drum from said boxing, to 55 enable substitution of other type-discs with variable printing characters at the type-heads 30, as may be desired in the use of the ticket-printing machine.

The revoluble platen drum, 52, has a cylindrical circumference the surface of which 60 is covered by a sheathing, 53, of rubber or other suitable material forming an impression bed, and in the improved construction according to my present invention the cylindrical circumferential surface of the

platen drum is provided with a transverse ridge at a point which will be coincident with the transverse set of type-heads 30 which constitute the impression members in the reverse revolution of the platen drum 70 and the head 34 of the main drive-shaft 16. Said ridge thus forms the platen bed in producing the impression and is the only point on the circumference of the platen drum at which a printing impression is made. The purpose of thus providing a definite transverse raised platen bed, as constituted by said ridge, is to afford an impression surface directly related to and co-acting with the printing set of type-heads and thus preclude smearing or blurring of the imprint under the relative revoluble movements of the platen drum and printing media.

The preferred construction for said impression ridge comprises a bar or block, 54, having a top surface, as at 55, forming the platen bed, beneath which the sides of the block are of dovetail contour, as at 56—56, 80 said block being inserted and seated beneath the surface sheathing 53 in a corresponding transverse dovetail recess or groove, 57, in the peripheral portion of the platen drum.

The operation and advantages of my improvements will be readily understood by those skilled in the art to which my invention appertains. Any desired alignment of the type-heads of the type-discs can be conveniently effected and maintained, to 85 produce the desired impression successively upon the units of the ticket-strip at each revolution of the main drive-shaft, without removal of the printing media from the head of said shaft.

90 It will be understood that in the types of ticket-printing machines to which my improvements especially relate, only one impression is made at each revolution of the main shaft carrying the printing media, and therefore the continuous ticket-strip 28 is intermittently locked in its passage through the machine from the feed-table 27 and released to permit each successive ticket-unit to pass through in position to receive 95 the impression. This control of the ticket-strip is effected by a laterally-acting spring-controlled catch, 58, mounted at the front of the feed-table and engaging with the usual edge-notches, as at 59, in the ticket-strip between each unit, said catch being operated in a release movement by a lateral cam-flange, 60, carried at the outer side of the platen drum at a point coincident with the 100 passage of the ticket-unit in receiving the printing impression. At a point corresponding to the cam-flange 60 in the reverse revoluble movement of the platen drum and the head of the main drive-shaft 16, said shaft-head carries upon the periphery of its inner wall or flange 36 a segmental periph-

105

120

125

130

erally-projecting plate, 61, bearing with relation to the cylindrical inner periphery, 62, of the platen drum and acting with pressure upon the ticket-strip during the 5 respective revolution of the parts to feed the ticket-strip forward between the plate 61 and periphery 62 while the strip is released for the duration of one ticket-unit from action of the locking-catch 58.

10 I do not desire to be understood as limiting myself to the detail features of construction and arrangement as herein shown and described, as it is manifest that variations and modifications therein may be resorted 15 to, in the adaptation of my invention to varying conditions of use, without departing from the spirit and scope of the invention and improvements. I therefore reserve the right to all such variations and modifications as properly fall within the scope 20 of my invention and the terms of the following claims:

Having thus described my invention, I claim and desire to secure by Letters Patent:

25 1. In a machine for printing tickets, a revoluble shaft, a printing-drum carried by said shaft and consisting of type-discs having a series of variable type-heads at their periphery, said type-discs being mounted in 30 transverse series on an axis eccentric to the axis of said shaft and respectively having an "idler" turnable movement independent of the rotary movement of said shaft, and means for respectively locking and retaining 35 each of said type-discs in constant fixed position against turnable movement at all times during the revolution of said main shaft, whereby the type-discs are in permanent fixed relation during operation of the 40 machine and variable only by manual adjustment.

45 2. In a machine for printing tickets, a revoluble shaft, a fixed shaft carried by said revoluble shaft on a plane eccentric to the axis thereof, a printing-drum consisting of type-discs having type-heads at their periphery and turnably mounted in transverse series upon said fixed shaft, and means 50 for respectively locking and retaining each of said type-discs in constant fixed position against turnable movement at all times during the revolution of said main shaft, whereby the type-discs are in permanent fixed relation during operation of the machine and variable only by manual adjustment.

55 3. In a machine for printing tickets, a revoluble shaft, a boxing member carried by said revoluble shaft, a printing-drum carried by said boxing and consisting of type- 60 discs having a series of variable type-heads at their periphery, said type-discs being mounted on an axis eccentric to the axis of said shaft and in transverse series between the end walls of said boxing and respectively having an "idler" turnable move- 65

ment independent of the rotary movement of said shaft, and means for respectively locking and retaining each of said type-discs in constant fixed position against turnable movement at all times during the revolution of said main shaft, whereby the type-discs are in permanent fixed relation during operation of the machine and variable only by manual adjustment.

4. In a machine for printing tickets, a 75 revoluble shaft, a boxing member carried by said revoluble shaft, a fixed shaft carried by said boxing on a plane eccentric to the axis of said revoluble shaft, a printing-drum carried by said boxing and consisting of type-discs having type-heads at their periphery and turnably mounted in transverse series between the end walls of said boxing and upon said fixed shaft, and means carried by said boxing and operative to respectively lock and retain each of said type-discs in constant fixed position against turnable movement at all times during the revolution of said main shaft, whereby the type-discs are in permanent fixed relation during operation of the machine and variable only by manual adjustment.

80 5. In a machine for printing tickets, a revoluble shaft having a recessed head, a boxing member secured to and seated in and carried by said recessed head, a printing-drum carried by said boxing and consisting of type-discs having type-heads at their periphery, said type-discs being mounted on 85 an axis eccentric to the axis of said shaft and in transverse series between the end walls of said boxing and respectively having an "idler" turnable movement upon their mounting on said boxing independent of the rotary movement of said shaft, and means for respectively locking and retaining 90 each of said type-discs in constant fixed position against turnable movement at all times during the revolution of said main shaft, whereby the type-discs are in permanent fixed relation during operation of the machine and variable only by manual adjustment.

95 6. In a machine for printing tickets, a revoluble shaft, a boxing member attachably and removably carried by said shaft, and printing media entirely carried by said boxing, said media comprising type-discs having a series of variable type-heads at their periphery and mounted on an axis eccentric 100 to the axis of said shaft and in transverse series between the end walls of said boxing, said type-discs respectively having a constant fixed position against turnable movement upon their mounting on said boxing at 105 all times during the revolution of said main shaft, whereby the type-discs are in permanent fixed relation during operation of the machine and variable only by manual adjustment.

70

85

90

100

7. In a machine for printing tickets, a revolute cylindrical platen drum having at its circumference a ridge extending transversely across the surface of the drum and projective from the periphery thereof, said transverse surface-ridge forming the platen bed and constituting the only point on the circumference of the drum at which a printing impression is made.
8. In a machine for printing tickets, a revolute cylindrical platen drum having at its circumference a transverse recess or groove in its periphery, and a bar or block longitudinally seated in said groove and forming a ridge extending transversely across the surface of the drum and projective from the periphery thereof, said trans-

verse surface-ridge constituting the platen bed at which the printing impression is made.

9. In a machine for printing tickets, a revolute platen drum having at its circumference a dovetail recess or groove extending transversely of the drum, and a dovetail bar or block keyed in said groove and having a projective platen surface forming a ridge extending transversely across the surface of the drum and projective from the periphery thereof, said transverse surface-ridge constituting the platen bed at which the printing impression is made.

In testimony whereof I have signed the foregoing specification.

JOHN ALWYN KELLER.
